(57) **CLAIM**

I claim the ornamental design for an electrical and aluminum tubing clamp, as shown and described.

DESCRIPTION

FIG. 1 is a perspective view of the electrical and aluminum tubing clamp;

FIG. 2 is a top plan view of the electrical and aluminum tubing clamp shown in FIG. 1;

FIG. 3 is a front elevational view of the electrical and aluminum tubing clamp shown in FIG. 1;

FIG. 4 is a right side elevational view of the electrical and aluminum tubing clamp shown in FIG. 1;

FIG. 5 is a bottom plan view of the electrical and aluminum tubing clamp shown in FIG. 1;

FIG. 6 is a rear elevational view of the electrical and aluminum tubing clamp shown in FIG. 1; and,

FIG. 7 is a left side view of the electrical and aluminum tubing clamp shown in FIG. 1.
